Primary Examiner—Alan P. Douglas*Assistant Examiner*—Robin V. Taylor*Attorney, Agent, or Firm*—Trask, Britt & Rossa**[57]****CLAIM**

The ornamental design for an accelerator vane for a centrifuge, as shown and described.

DESCRIPTION

FIG. 1 is a view in perspective of the invention;
FIG. 2 is a rear view thereof;
FIG. 3 is a front view thereof;
FIG. 4 is a right side view thereof;
FIG. 5 is a left side view thereof;
FIG. 6 is a bottom view thereof; and,
FIG. 7 is a top plan view thereof.
